CLAIM

We claim the ornamental design for a case for charging an aerosol generator, as shown and described.

DESCRIPTION

FIG. 1 is a top, front, left perspective view of a case for charging an aerosol generator showing the claimed design; FIG. 2 is a bottom, front, right perspective view thereof; FIG. 3 is a top view thereof; FIG. 4 is a bottom view thereof; FIG. 5 is a front view thereof; FIG. 6 is a rear view thereof; FIG. 7 is a left view thereof; and, FIG. 8 is a right view thereof.

The broken lines in the drawings illustrate portions of the case for charging an aerosol generator that form no part of the claimed design.

1 Claim, 8 Drawing Sheets
